Atty.

UNITED STATES PATENT OFFICE

HENRY M. SIEGEL, OF MALDEN, MASSACHUSETTS

TOOTHERBRUSH HOLDER

Application filed September 10, 1927. Serial No. 218,592.

The invention has relation in particular to tooth brush holders, and has as its object to provide a novel and improved holder or repository for tooth brushes and the like articles, within which they may be placed when not in use, to keep them out of the way and allow them to air and dry out without contamination by dust or contact with other objects.

10 To this end, the device of the invention comprises a brush-holding body, and a transparent front or facing. The said body is composed of stiff sheet-material preferably sheet-metal, that is bent to form the back, top, 15 and bottom of the holder, the free edges of such top and bottom being provided with marginal lips or flanges. The front or facing is composed of flexible transparent material. It is confined between the said top 20 and bottom of the body, and is retained by the said lips or flanges. An opening in the bottom of the body, and brush-supporting notches in said bottom radiating from said opening, provide for the insertion of the 25 heads of the brushes into the holder, and for the support and retention of the brushes.

Illustrative embodiments of the invention are shown in the accompanying drawings, in which,—

30 Fig. 1 is a front view of a holder constructed according to the invention, with a tooth brush applied thereto.

Fig. 2 is a view in vertical section on line 2, 2, of Fig. 1.

35 Fig. 3 is a view of the holder in horizontal section on line 3, 3, of Fig. 1.

Fig. 4 is a front view showing a modification.

In accordance with the invention, the blank 40 for the body of my tooth-brush holder is bent so that its intermediate portion constitutes a back 1 and its end-portions constitute a top 2 and bottom 3, respectively, the said top and bottom projecting forward from the 45 back. The free margins of the top and bottom are curved, in this instance symmetrically in an arc of a circle. The lips or flanges that are provided upon the said margins may be either narrow tongues as at 4, 4, in Figs. 50 1, 2 and 3, or substantially continuous flanges

as at 41, 41, Fig. 4. At 5, Figs. 2 and 3, is the opening in the bottom 3 to permit the heads of brushes to be passed up into the interior of the holder, the said opening being shown best in Fig. 3, and at 6, 6, Fig. 3, are the 55 notches in the said bottom, radiating from the opening 5, and respectively adapted to receive the neck-portion of a brush 7 as in Figs. 1 and 3. A tooth brush 7 is quickly and easily put in place in the holder by inserting the head thereof from below up through opening 4, moving its neck laterally outward through the narrow portion of a notch 5, and releasing it to rest with the flaring portion of the material in which the bristles are inserted resting upon the side-edges of the notch 5.

The transparent front or facing 9 is made preferably of a heavy grade of clear and colorless sheet celluloid, although some other flexible transparent material may be employed. The flexibility facilitates assembling the device in the first place, and in removing it for the purpose of cleaning the holder. It is located between the top 2 and bottom 3, 75 and confined by the lips or flanges 4 or 41, and may be easily inserted by rolling it into a cylinder, pushing it upward through the opening 5 in the bottom, and then releasing it to let it spring out into the position shown 80 in Fig. 1, against the lips or flanges 4 or 41 as the case may be. Or it may be slipped endwise in between the lips 4, 4, of Figs. 1, 2, 3, or at the places where the width of the flanges 41, 41, of Fig. 4 is reduced. It may 85 be removed to clean the inner surface thereof, and the interior of the holder, by a reversal of this procedure.

The use of transparent material for the front 9 not only makes it possible to see the 90 objects which are within the holder and what one is doing in the process of inserting or removing a tooth brush, and makes apparent the state of cleanliness of its interior, but lets in light to assist in keeping the brushes and 95 holder clean and sanitary. The sheet-metal of the back, top, and bottom is preferably enameled white on inside and out. The large opening 5 in the bottom admits plenty of air at all times, without letting dust or other con- 100

tamination fall on the bristles. The shape makes the device very compact, it being adapted to be mounted close against a wall. 8. In this instance, slots 10, 10, in the shape 5 of inverted keyholes, are made in the back 1, to enable the holder to be removably mounted on the heads of screws 11, 11, driven into the wall.

10 The form of the device shown, that of a half-cylinder, is the preferred one, because of the special advantages set forth; however, in practice the form may be varied to meet special requirements without departure from the scope of the invention.

15 What I claim as my invention is,—

1. A tooth-brush holder composed of bendable material bent to form a back, top, and substantially horizontal bottom, the bottom having an opening through which the head of 20 a tooth brush may be introduced from below, and formed with a notch to receive the neck below such head, and both top and bottom being formed with vertical marginal flanges, and a front of transparent material 25 confined between said top and bottom, resting upon said bottom, and retained by said marginal flanges.

2. A tooth-brush holder composed of bendable material bent to form a body-portion, 30 top, and substantially horizontal bottom, the bottom having an opening to permit the head of a tooth brush to be introduced from below, and having also a notch communicating with said opening to receive the neck below such 35 head, and both top and bottom being formed with vertical marginal flanges, and a removable front of flexible transparent material adapted by reason of its flexibility to be rolled up for introduction through the said 40 opening in the bottom and to be retained by the said marginal flanges when expanded between said top and bottom.

HENRY M. SIEGEL.
